[57] CLAIM

The ornamental design for adjustable pants, as shown and described.

DESCRIPTION

FIG. 1 is a front elevational view of adjustable pants,
folded to be worn; showing our new design;

FIG. 2 is an inside elevational view thereof; the pants
shown open;

FIG. 3 is a left side elevational view of FIG. 2; the right side being a mirror image thereof;

FIG. 4 is an outside elevational view of FIG. 2;

FIG. 5 is a top plan view of FIG. 2;

FIG. 6 is a bottom plan view of FIG. 2.

FIG. 1

FIG. 3
